DESIGN FOR A FAUCET ATTACHMENT

Carl E. Lehman, Chicago, Ill.

Application April 29, 1940, Serial No. 92,031

Term of patent 14 years

To all whom it may concern:

Be it known that Carl E. Lehman, a citizen of the United States of America, residing at Chicago, in the county of Cook and State of Illinois, has invented a new, original, and ornamental Design for a Faucet Attachment, of which the following is a specification, reference being had to the accompanying drawing, forming part thereof.

Fig. 2 is an elevational view of the faucet attachment on Fig. 1.

Fig. 3 is a bottom plan view of the faucet attachment shown in Fig. 1.

I claim:

The ornamental design for a faucet attachment, as shown.

CARL E. LEHMAN.
